UNITED STATES PATENT OFFICE.

CHARLES LEWIS RICE, OF CHIPPEWA COUNTY, MINNESOTA.

PAPER-FOLDING MACHINE.

No. 870,903.

Specification of Letters Patent.

Patented Nov. 12, 1907.

Application filed June 10, 1907. Serial No. 378,230.

To all whom it may concern:

Be it known that I, CHARLES LEWIS RICE, a citizen of the United States, residing in the county of Chippewa and State of Minnesota, have invented certain new and useful Improvements in Paper-Folding Machines, of which the following is a specification.

My present invention pertains to improvements in paper-folding machines, the construction and advantages of which will be hereinafter set forth, reference 10 being had to the annexed drawings, wherein:

Figure 1 is a transverse vertical sectional view of the machine, taken on the line 1—1 of Fig. 2; Fig. 2 a front elevation of the machine, portions being broken away to more clearly illustrate certain parts; Fig. 3 a transverse vertical sectional view taken on the line 3—3 of Fig. 2, and illustrating more particularly the stacker mechanism and one of the flexible aprons which, in conjunction with a fixed board, forms the pocket into which the first folder descends carrying with it the 15 paper, once folded; Fig. 4 a longitudinal vertical sectional view, taken on the line 4—4, Fig. 1, and looking toward the rear of the machine; Fig. 5 a horizontal sectional view on the line 5—5 of Fig. 1; Fig. 6 a perspective view of the first and third folders, the oscillating member of the stacker and the mechanism for operating such parts; Fig. 7 a similar view of the movable abutment or holder for the folded papers; Fig. 8 a perspective view of the second and fourth folders and the mechanism for operating the same; and Fig. 9 a vertical 20 sectional view illustrating a different form of stacker which is employed with a three-folder machine.

The main object of the present invention is to provide a simple and compact machine for folding papers, the machine being operable by foot power, so that it may 25 be employed in small plants where power is not available; the machine may, however, be driven by power.

A further object of the invention is to provide a simple and efficient mechanism for making the various folds, said mechanism embodying in addition to the 30 folding blade or knife a fixed and a yielding wall, the latter yielding or moving outwardly to a slight extent each time a folded paper is forced down between the walls by the blade, whereby the folded edge of the paper will be grasped and held as the blade is withdrawn from between the folds. The yielding side or 35 apron will also move out to a considerable extent in case a paper should be distorted and forced downward between the walls by the blade whereby injury to the parts will be obviated.

50 A still further object of the invention is to provide a stacker for the folded papers, the stacker being timed to work in conjunction with the last folder of the machine.

With these and other objects in view a detail descrip-

tion of the invention will be given, reference being had 55 to Figs. 1 to 8 inclusive, which show a four-fold machine.

The table or bed of the machine is designated by 1 and is supported by legs 2 connected by suitable longitudinal sills 3 and cross-pieces or braces 4. Other supports and braces are employed and will be hereinafter pointed out. A shelf 5 extends along the front of the machine, while a shelf 6 is arranged in the rear of the machine.

Figure 1 is a transverse vertical sectional view of the machine, taken on the line 1—1 of Fig. 2; Fig. 2 a front elevation of the machine, portions being broken away to more clearly illustrate certain parts; Fig. 3 a transverse vertical sectional view taken on the line 3—3 of Fig. 2, and illustrating more particularly the stacker mechanism and one of the flexible aprons which, in conjunction with a fixed board, forms the pocket into which the first folder descends carrying with it the paper, once folded; Fig. 4 a longitudinal vertical sectional view, taken on the line 4—4, Fig. 1, and looking toward the rear of the machine; Fig. 5 a horizontal sectional view on the line 5—5 of Fig. 1; Fig. 6 a perspective view of the first and third folders, the oscillating member of the stacker and the mechanism for operating such parts; Fig. 7 a similar view of the movable abutment or holder for the folded papers; Fig. 8 a perspective view of the second and fourth folders and the mechanism for operating the same; and Fig. 9 a vertical sectional view illustrating a different form of stacker which is employed with a three-folder machine.

The main object of the present invention is to provide a simple and compact machine for folding papers, the machine being operable by foot power, so that it may be employed in small plants where power is not available; the machine may, however, be driven by power. 25 A further object of the invention is to provide a simple and efficient mechanism for making the various folds, said mechanism embodying in addition to the folding blade or knife a fixed and a yielding wall, the latter yielding or moving outwardly to a slight extent each time a folded paper is forced down between the walls by the blade, whereby the folded edge of the paper will be grasped and held as the blade is withdrawn from between the folds. The yielding side or apron will also move out to a considerable extent in case a paper should be distorted and forced downward between the walls by the blade whereby injury to the parts will be obviated.

50 A still further object of the invention is to provide a stacker for the folded papers, the stacker being timed to work in conjunction with the last folder of the machine.

With these and other objects in view a detail descrip-

tion of the invention will be given, reference being had 55 to Figs. 1 to 8 inclusive, which show a four-fold machine.

The table or bed of the machine is designated by 1 and is supported by legs 2 connected by suitable longitudinal sills 3 and cross-pieces or braces 4. Other supports and braces are employed and will be hereinafter pointed out. A shelf 5 extends along the front of the machine, while a shelf 6 is arranged in the rear of the machine.

Figure 1 is a transverse vertical sectional view of the machine, taken on the line 1—1 of Fig. 2; Fig. 2 a front elevation of the machine, portions being broken away to more clearly illustrate certain parts; Fig. 3 a transverse vertical sectional view taken on the line 3—3 of Fig. 2, and illustrating more particularly the stacker mechanism and one of the flexible aprons which, in conjunction with a fixed board, forms the pocket into which the first folder descends carrying with it the paper, once folded; Fig. 4 a longitudinal vertical sectional view, taken on the line 4—4, Fig. 1, and looking toward the rear of the machine; Fig. 5 a horizontal sectional view on the line 5—5 of Fig. 1; Fig. 6 a perspective view of the first and third folders, the oscillating member of the stacker and the mechanism for operating such parts; Fig. 7 a similar view of the movable abutment or holder for the folded papers; Fig. 8 a perspective view of the second and fourth folders and the mechanism for operating the same; and Fig. 9 a vertical sectional view illustrating a different form of stacker which is employed with a three-folder machine.

The main object of the present invention is to provide a simple and compact machine for folding papers, the machine being operable by foot power, so that it may be employed in small plants where power is not available; the machine may, however, be driven by power. 25 A further object of the invention is to provide a simple and efficient mechanism for making the various folds, said mechanism embodying in addition to the folding blade or knife a fixed and a yielding wall, the latter yielding or moving outwardly to a slight extent each time a folded paper is forced down between the walls by the blade, whereby the folded edge of the paper will be grasped and held as the blade is withdrawn from between the folds. The yielding side or apron will also move out to a considerable extent in case a paper should be distorted and forced downward between the walls by the blade whereby injury to the parts will be obviated.

50 A still further object of the invention is to provide a stacker for the folded papers, the stacker being timed to work in conjunction with the last folder of the machine.

With these and other objects in view a detail descrip-

tion of the invention will be given, reference being had 55 to Figs. 1 to 8 inclusive, which show a four-fold machine.

The table or bed of the machine is designated by 1 and is supported by legs 2 connected by suitable longitudinal sills 3 and cross-pieces or braces 4. Other supports and braces are employed and will be hereinafter pointed out. A shelf 5 extends along the front of the machine, while a shelf 6 is arranged in the rear of the machine.

Figure 1 is a transverse vertical sectional view of the machine, taken on the line 1—1 of Fig. 2; Fig. 2 a front elevation of the machine, portions being broken away to more clearly illustrate certain parts; Fig. 3 a transverse vertical sectional view taken on the line 3—3 of Fig. 2, and illustrating more particularly the stacker mechanism and one of the flexible aprons which, in conjunction with a fixed board, forms the pocket into which the first folder descends carrying with it the paper, once folded; Fig. 4 a longitudinal vertical sectional view, taken on the line 4—4, Fig. 1, and looking toward the rear of the machine; Fig. 5 a horizontal sectional view on the line 5—5 of Fig. 1; Fig. 6 a perspective view of the first and third folders, the oscillating member of the stacker and the mechanism for operating such parts; Fig. 7 a similar view of the movable abutment or holder for the folded papers; Fig. 8 a perspective view of the second and fourth folders and the mechanism for operating the same; and Fig. 9 a vertical sectional view illustrating a different form of stacker which is employed with a three-folder machine.

The main object of the present invention is to provide a simple and compact machine for folding papers, the machine being operable by foot power, so that it may be employed in small plants where power is not available; the machine may, however, be driven by power. 25 A further object of the invention is to provide a simple and efficient mechanism for making the various folds, said mechanism embodying in addition to the folding blade or knife a fixed and a yielding wall, the latter yielding or moving outwardly to a slight extent each time a folded paper is forced down between the walls by the blade, whereby the folded edge of the paper will be grasped and held as the blade is withdrawn from between the folds. The yielding side or apron will also move out to a considerable extent in case a paper should be distorted and forced downward between the walls by the blade whereby injury to the parts will be obviated.

50 A still further object of the invention is to provide a stacker for the folded papers, the stacker being timed to work in conjunction with the last folder of the machine.

With these and other objects in view a detail descrip-

is adjustably attached to one of the sills 3. By this means the bar or column 26 may be tilted slightly and as a consequence the blade 8 may be brought to its proper position. A bracket or arm 28, Fig. 2, is secured to the bed and extends outwardly along one side of the folder-blade 8, the bracket being provided at its outer end with an overhanging finger 29, between which and the bracket the blade passes as it nears its limit of upward movement. The guide thus formed

10 serves to steady and direct the movement of the blade,

The main driving shaft 30 receives its motion from a power shaft 31 and interposed pinion 32 and gear 33, shaft 31 carrying at one end a crank 34 which is connected to the treadle 35 by a pitman 36. Shaft 31 also 15 carries a fly-wheel 37.

Mounted upon and rotatable with shaft 30 are two double or wing-shaped cams 38 and 39, cam 38 operating the mechanism which controls the first and third folders (8 and 20) and also the oscillating member of 20 the packer, these parts being shown in detail in Fig. 6.

Journaled upon a shaft 40, Figs. 1 and 5, at a point below the cam 38, is an arm or lever 41 having two curved fingers or cam faces, 42 and 43 designed to coact with the wings of cam 38 as the same is rotated in the 25 direction of the arrow, Figs. 1 and 6. To the lower end of the arm or lever 41 is pivotally connected a link 44, which in turn is pivoted to the short arm 45 of a bell-crank lever secured to a shaft 46, the long arm 47 of the lever being connected with the lower end of a link or 30 pitman 48, the opposite end of which is pivotally connected with the slide 25 which operates the first folder 8.

An arm 49, secured to shaft 46, is pivotally connected to a pitman 50, the latter being similarly connected to an arm 51, secured to a vertically-disposed shaft 52.

35 To the upper end of said shaft is secured an arm 53 and a pitman or link 54 is interposed between said arm and the third folder 20. Said folder is provided with sleeves 55 which embrace a rod 56, Fig. 5, that extends lengthwise of the machine and upon which the folder is moved 40 back and forth. When the folder 20 is retracted it is maintained in its horizontal position by a shelf or bracket 57, Figs. 4 and 5, which is secured upon a cross piece 58.

An arm 59 is secured to shaft 46, the arm being connected by a link 60 with the upper end of an arm 61 secured to a rocker-shaft 62. An arm 63 extends upwardly from the shaft and carries the plate 64, which forms the oscillating member of the packer. A counterweight 65 is mounted on a threaded arm 66, secured 50 to shaft 46, see Figs. 1, 4 and 5, said weight acting to balance the parts and render the action of the same relatively easy. By having the cam or curved face 42 made relatively long the cam 38 moves the same at a relatively slow speed, this taking place when the folders are operating, the long face also affording increased leverage. 55 The face 43 is short and as the cam 38 strikes it, a relatively quick return movement of the parts is effected.

Pivoted upon a short shaft 67, Fig. 5, or other suitable support, is an arm 68, carrying at its upper end 60 curved fingers or cam faces 69 and 70, see Fig. 8, adapted to coact with the winged cam 39. A link 71 connected to the lower end of arm 68 is in turn connected to an arm 72 at about its midlength, the arm being secured to a rocker-shaft 73, journaled in the framing of the 65 machine. A link 74 is pivotally connected to the

upper end of arm 72, the link extending downwardly and being connected to a slide 75 which carries the second folder 15. Said slide is mounted and movable in a horizontally-disposed way or support 76 secured to the upright framing of the machine. A guide and 70 sustaining finger 77, Figs. 1, 2 and 5, is provided for the folder 15.

A short arm 78 is secured to shaft 73 and a link 79 connects said arm with a lever 80. Said lever is connected to an arm 81, the parts being fulcrumed at their 75 point of connection on a bracket 82 secured to the forward sill 3, see Figs. 2 and 5. A pitman or link 83 connects the outer end of the arm 81 with a slide 84 to which the fourth or final folder 24 is attached. Said slide is mounted in a vertically-disposed supporting 80 bar or column 85, Figs. 4 and 5, the upper end of the column passing through an opening formed in the table 21, while the lower end is held by a bolt 86 made adjustable so that the column may be properly positioned. A counterweight 87 is secured to shaft 73. 85

Secured beneath table 21 and to one side of the opening formed therein, see Fig. 3, is an open frame composed of an upper cross-bar 88, the under edge of which is curved, and a lower round cross-bar 89, the latter being held in position by depending wings, 90. 90 The papers which are given their last fold by the blade 24 as they are passed through the opening formed in the table 21, come in front of the bar 88 and cross-bar or rod 89. After the blade is retracted or elevated, the push-plate 64 forces the folded paper between the 95 lower rounded portion of the cross-bar 88 and the round cross-bar 89 and against a plate or abutment 91, extending upward from a frame 92, carried by a pair of arms 93, said arms being provided at their lower ends with half-boxes 94, which rest upon the shaft 62. 100

Extending outward from the frame 92 at the lower end of the abutment 91 are two curved or radius arms 95 which work immediately below the cross-rod or bar 89 and serve to support the papers, as clearly shown in Fig. 3. An arm 96 also extends outwardly from the 105 frame 92 at a point below the radius arms 95 and to the outer end of said arm 96 is connected a rope or cable 97 which passes about a pulley 98 arranged in the lower portion of the frame and over a second pulley 99 secured in a bracket located beneath the main table. 110 The cord or rope then extends downwardly between two guide-ways 100 and 101 (see Fig. 2), passing freely through weights 102, 103, and being connected to a weight 104 arranged in the lower portion of the guide-ways. Stops 105 and 106 arrest the downward movement of the upper weights 102 and 103, the lower weight 104 at all times exerting force upon the rope or cable. As the folded papers increase in number and come to rest upon the curved or radius arms 95, the 115 arms 93 with the frame and abutment member 91 will be swung outward and as a consequence the weight 104 will be raised. As the papers accumulate they will have a tendency to throw the arms and frame downward, but as the frame swings the weight 104 will come into contact with weight 103 and raise the 120 same off its support, thereby adding the amount of the weight 103 to the cord 97, whereby the frame with the added weight of the papers will be counterbalanced. A further downward movement of the frame will carry 125 weight 103 against weight 102, lifting the same from 130

its support 105, so that as the papers increase in bulk and weight the counterbalancing thereof is automatically effected.

It is thought that the operation of the machine will 5 be clearly understood from the foregoing description, but a short resume thereof will be given. The two cams 38 and 39 are set quartering upon shaft 30 so that the first and third folders are first actuated and then withdrawn and after they come to rest the second and 10 fourth folders are actuated by the cam 39. The push-plate 64 comes into action at the same time the first and third folders are operated, the fourth folder 24 at such time being elevated and out of the path of the push-plate which serves to force the last completely-folded paper between the bar 88 and rod 89 and against the stack of papers previously folded. This cycle of 15 operation continues so long as the papers are fed to the machine and power is applied thereto.

In Fig. 9 a slightly modified construction is shown. 20 In this instance the fourth folder is done away with and the papers are carried over a table 107 by the third folder. The table, as will be noted, is provided with an opening 108, the lower portion of which is slightly less in dimensions than the folded papers. A push-plate 109 works through the opening and after the third 25 folder is retracted moves downwardly to push the papers through the opening and onto a plate 110 carried by a bracket 111 slidably mounted upon a rod 112. The bracket is thrown upwardly by a cord or cable 30 113 which passes over a pulley 114, the cord acting with a series of weights, as in the construction above described. The plate 109 is carried by an arm 115 also slidably mounted upon the rod 112. A link or rod 116 is pivotally connected to arm 115 and to an 35 arm 117 fulcrumed upon a bracket 118 secured to the frame of the machine. Rocking motion is imparted to the arm through a link 119 and an arm 120 pivotally connected to the link and secured at the opposite end upon the shaft 73 which is the same as the corresponding 40 shaft in the main form of the machine above described.

It is conceivable, of course, that in so far as the details of the invention are concerned they may be modified in part without departing from the spirit of 45 the invention.

Having thus described my invention, what I claim is:

1. In a folding machine, the combination of a fixed wall forming one member of a folding slot; a flexible apron 50 arranged adjacent thereto; means for placing said apron under a yielding tension; and a folding-blade adapted to work between the wall and the apron.

2. In a machine for folding papers, the combination of a fixed wall; an apron secured adjacent to one end thereof; 55 said apron extending alongside of the wall; means for maintaining the apron in a stretched condition; and a folding-blade passing down between the apron and the wall.

3. In a machine for folding papers, the combination of 60 a fixed wall; an apron secured adjacent to one end of said wall and extending alongside of one face thereof; a spring serving to keep said apron taut; and a folding-blade adapted to work between said fixed wall and the apron.

4. In a machine for folding papers, the combination of 65 a fixed wall; an apron having one end secured adjacent to one end of the wall; a fixed support arranged adjacent to the other end of the wall and over which the apron is drawn; means for placing said apron under tension; and

a folding-blade adapted to pass between the apron and the fixed wall. 70

5. In a machine for folding papers, the combination of a fixed wall provided with a slot or opening therein for the passage of a folder transversely to the wall; a pair of aprons arranged adjacent to the face of the wall upon opposite sides of the slot or opening thereof; means for placing said aprons under tension; a folder adapted to pass down between said aprons and the wall; and a second folder adapted to pass at right angles to the path of movement of the first folder and to carry each folded paper through the slot in the wall. 75

6. In a machine for folding papers and the like, the combination of a fixed member provided with a slot or opening therein; a pair of aprons lying adjacent to one face of said fixed member and upon opposite sides of the slot therein; a folder-blade adapted to pass in between 80 said aprons and the fixed member; a second folder-blade adapted to pass through the slot in the fixed member; and a receiver for the folded papers located beneath the slot and in the path of movement of the second folder-blade.

7. In a machine for folding papers, the combination of 85 folding mechanism; and a receiver comprising a swinging member carrying an abutment plate, a pair of curved arms extending outwardly therefrom, means for holding said member toward the folding mechanism, and a push-plate adapted to transfer 90 the folded paper from the position in which it was left by the folder against the abutment-plate or the previously-folded, transferred paper. 95

8. In a machine for folding papers, the combination of 100 folding mechanism; an open frame arranged adjacent to the folding mechanism and against which the folded paper is deposited, the opening in the frame being slightly less than the dimensions of the folded paper; a swinging frame arranged adjacent to the open frame; means for urging the swinging frame toward the open frame; supporting 105 members carried by the swinging frame; and a push-plate adapted to force the folded papers through the opening in the fixed frame and onto the supporting members carried by the swinging frame.

9. In a machine for folding papers, the combination of 110 folding mechanism; a fixed frame arranged adjacent to the folding mechanism against which the folded paper is adapted to be deposited, said fixed frame having an opening therein of a size slightly less than that of the folded paper; a swinging frame; means for urging said swinging 115 frame toward the fixed frame; a pair of curved arms extending outwardly from the swinging frame beneath the fixed frame; and a push-plate adapted to be projected against the folded paper and to carry the same through the opening in the fixed frame and onto the arms carried by the swinging frame. 120

10. In a machine for folding papers, the combination of 125 folding mechanism; a fixed frame arranged adjacent thereto, said frame being provided with an opening slightly less in size than the folded paper; a swinging frame arranged in rear of the fixed frame; a pair of curved arms extending outwardly from the swinging frame at a point immediately below the fixed frame; a series of pick-up weights connected to the swinging frame; a push-plate adapted to force the papers through the opening in the fixed frame, and to deposit them upon the arms of the swinging frame; and means for periodically operating said push-plate. 130

11. In a machine for folding paper, the combination of 135 a bed; a supporting column passing through an opening formed therein; a bolt secured to the lower end of said column; means for securing longitudinal adjustment of the bolt, whereby the inclination of the column may be varied; a slide mounted within the column; and a folder-blade carried by the slide.

12. In a machine for folding papers, the combination of 140 a main operating shaft; a pair of winged cams carried thereby; a folding-blade adapted to form the first fold in a paper; another folding-blade adapted to form the third fold in the paper; a push-plate; connections intermediate said parts and one of the cams for operating said members in unison and positively in both directions; a folder-blade for forming the second fold in the paper; a fourth folder-blade for forming the fourth fold in the paper; 145

- connections intermediate said parts and the second cam, for operating said blades in unison and positively in both directions; and a receiver or stacker for the folded papers, into which the papers are projected by the push-plate.
- 5 13. In a machine for folding papers, the combination of a suitable bed or frame for supporting the parts; a main operating shaft provided with a pair of cams; a blade for forming the first fold in a paper; a blade for forming the third fold in the paper; a push-plate; connections intermediate said parts and one of the cams for moving said parts in unison; a blade for forming the second fold in the paper; a blade for forming the fourth fold in the paper; connections intermediate said parts and the second cam for operating the parts in unison and while the first 10 and third folding-blades and the push-plate are at rest and in their retracted positions; a swinging frame arranged to one side of the path of travel of the fourth folding-blade and adapted to receive the papers moved thereon by the push-plate; and means for counterbalancing said frame as 15 it is swung outwardly by the increasing number of folded papers deposited thereon.
14. In a machine for folding papers, the combination of folding mechanism; a member located adjacent thereto, said member having an opening therein of a size slightly less than that of the folded paper; a movable abutment or holder for the folded papers; a push-plate adapted to force the folded papers through the opening and onto the holder; and a series of pick-up weights connected to the movable abutment and serving as the load upon the abutment increase^s to be successively brought into action and to thereby substantially counterbalance the abutment.
- 20 15. In a folding machine, the combination of a fixed

member forming one wall of a folding slot; a flexible apron arranged adjacent to said member and forming the opposite wall of the folding slot; means for maintaining 35 said apron under tension; a folding blade adapted to work between the fixed member and the apron; and a roughened surface located adjacent to the lower portion of the fixed member and serving to hold the folded paper as the blade is withdrawn from between the folds of the paper, substantially as described.

16. In a folding machine, the combination of a fixed member forming one wall of a folding slot; a flexible apron standing adjacent to said member and substantially coextensive therewith, said apron forming the opposite 45 wall of the folding slot; and yielding means for normally holding said apron in a stretched condition.

17. In a folding machine, the combination of a fixed member forming one wall of a folding slot, said member being provided with a slot or opening; a pair of flexible 50 aprons standing adjacent to the fixed member upon opposite sides of the slot, each of said aprons being substantially coextensive with that portion of the fixed member with which it coats; a folder for carrying the paper between said fixed member and the aprons; and a second folder acting to force the folded paper through the opening and to form a second fold therein.

In testimony whereof I have signed my name to this specification in the presence of two subscribing witnesses.

CHARLES LEWIS RICE.
